(57) CLAIM

The ornamental design for a gas cylinder valve body, as
shown and described.

DESCRIPTION

FIG. 1 is a top perspective view of a gas cylinder valve body
showing my new design;

FIG. 2 is a front elevational view thereof;

FIG. 3 is a side elevational view thereof, the opposite side
elevational view being identical;

FIG. 4 is a rear elevational view thereof;

FIG. 5 is a top plan view thereof; and,

FIG. 6 is a bottom plan view.

The broken line showings are for illustrative purposes only
and form no part of the claimed design.
